UNITED STATES PATENT OFFICE.

GEORGE R. SCHOENTHALER, OF CHICAGO, ILLINOIS.

SUPPORT AND TIE FOR CONCRETE-REINFORCING BARS.

1,119,123.

Specification of Letters Patent.

Patented Dec. 1, 1914.

Application filed May 31, 1913. Serial No. 771,115.

To all whom it may concern:

Be it known that I, GEORGE R. SCHOENTHALER, a citizen of the United States, residing at the city of Chicago, county of Cook, State of Illinois, have invented a certain new and useful Improvement in Supports and Tie for Concrete-Reinforcing Bars, of which the following is a full, clear, and exact description, such as will enable others skilled in the art to which it appertains to make and use the same, reference being had to the accompanying drawings, forming part of this specification, in which—

Figure 1 is a perspective view of a combined concrete reinforcing bar support and tie of my improved construction. Figs. 2, 3, and 4 are side elevational views of modified forms of the combined support and tie. Fig. 5 is a perspective view of a further modified form of the combined support and tie. Figs. 6, 7, 8, 9, 10, and 11 are perspective views of modified forms of my improved support and tie, which views show the combined support and tie formed of a piece of sheet metal, the same being cut and bent into proper shape. Fig. 8^a is a side elevational view of the form of support and tie seen in Fig. 8. Fig. 9^a is a side elevational view of the form of combined support and tie seen in Fig. 9. Fig. 12 is a side elevational view of a combined support and tie of my improved construction used in connection with reinforcing bars occupying a vertical plane, as is the case in the reinforcement of concrete walls.

My invention relates generally to reinforced concrete construction and more particularly to a support and tie for the metal rods used in reinforcing concrete floors, ceilings, walls and like structures.

My present invention is an improvement upon the combined support and tie disclosed in my copending application filed April 4, 1913, Serial No. 758,837.

In reinforcing concrete floors, ceilings, and walls, it is desirable, and in nearly all instances, essential, that the reinforcing rods be supported in a plane, above or away from the temporary flooring or form upon which the concrete is laid and to this end I have devised a comparatively simple, strong and inexpensive one piece support and tie, which can be readily combined with reinforcing rods and which will maintain the same a substantial distance above the floor or form,

while the concrete in plastic condition is being poured or distributed thereupon.

The principal object of my invention is to provide a combined support and tie which will automatically grip and engage the supported rod or rods to effectively hold the same in proper position, which gripping effect is obtained by reason of the weight of the supported rods, which weight acting upon the support and tie causes the same to perform the functions of a lever with one end resting upon the surface of the false work or form and with the other end gripping the supported rod.

Where the combined support and tie is utilized in connection with a pair of crossed rods, the upper portion of the device grips the upper one of the rods and the lower rod forms a fulcrum for said device.

Other objects of my invention are, to form a combined support or chair from wire or sheet metal, which can be readily cut and bent to proper shape; to provide a device which can be readily combined with the reinforcing rods, and which will effectively hold said rods against lengthwise movement; and, to provide a device which is practically skeleton in form and around which the plastic concrete will readily flow so that said device will be wholly embedded in the concrete when the same has become hardened.

With the above and other objects in view my invention consists in certain novel features of construction and arrangement of parts hereinafter more fully described and claimed.

In the form of the device shown in Fig. 1 the combined support and tie is formed from a single length of wire, shaped so as to support and tie together two reinforcing rods which are arranged substantially at right angles to each other. In this form of the device a section of wire of suitable size and length is bent at its center to form a semicircular part 1, which is adapted to engage over and grip the upper reinforcing rod A. From this bent central part 1, a section of wire extends downward to form the parallel legs 2 which occupy an angle of approximately 45° relative to a vertical plane and the lower portions of these legs are bent into semicircular form to provide curved seats 3 for the lower reinforcing rod B. From these curved seats the wire of

which the combined support and tie is formed, is extended upward to form the short vertically disposed legs 4, the upper portions of which occupy a plane slightly 3 above the plane occupied by the top of the part A. The end portions of the section of wire of which the device is formed are bent 10 downward in front of the legs 4 to form the vertically disposed parallel legs 5, and the lower ends thereof, which terminate in short 15 dists, see below, the curved seats 3 are adapted to rest directly upon the false work or the form which supports the floor or ceiling. In applying this particular form of support 20 and tie the rods A and B are lifted a short distance above the false work or form and the device is slipped over the upper rod A and then manipulated so that the upper portions of the legs 4 and 5 are brought up to 25 the sides of the rods A with the rod B resting upon the curved portion 3. The rods A and B are now permitted to move downward until the lower ends of the legs 5 rest upon the false work or form and the weight 30 of said rods transmitted through the device automatically brings about a gripping action of the device upon both rods. The upper bar is gripped by the curved portion 1 of the device, and the lower bar B which 35 performs the function of a fulcrum is gripped by the curved seats 3. If desired, a tie member α such as a wire nail may be inserted between the upper portions of the legs 4 and 5 above the supported rod A, but it has been demonstrated in practice that 40 this member is not essential.

In the form of the device illustrated in Fig. 2 the legs 4 are disposed with and the legs 5 are formed by bending the ends of 45 the section of wire directly downward from the forward ends of the curved seats 3.

The device illustrated in Fig. 3 is designed for supporting a single rod and where such construction is used the seat 3² is made comparatively small so as to accommodate a supporting member β such as a wire nail or the like, and which supporting member performs the function of a fulcrum for the combined support and tie and acts 50 as a support for the single reinforcing rod.

The form of the device illustrated in Fig. 4 is designed for supporting a single rod and where such construction is used a supporting member such as a wire nail β occupies the curved seats 3² and a transverse tie or keeper δ such as a wire nail is positioned above the supported rod and between the upper portions of the legs 4 and 5.

The form of the device illustrated in Fig. 5 is designed for supporting and tying together a pair of crossed rods and in this form of the device the legs or member 3² occupy vertical positions instead of inclined 55 positions as in the forms of the device illustrated in Fig. 1 and the upper portions of

said legs 3² are bent downwardly at an angle and are united by a straight transverse member 1² which rests directly upon the top of the upper pair A.

The device illustrated in Figs. 2 to 5 including 70 slightly in structural details, illustrate the same in principle and results as the device illustrated in Fig. 1.

In the construction illustrated in Fig. 6 the upper 1 and lower 1² formed from a single 75 pair of short metal or the like of a strap bent to form a pair of parallel legs 6, the upper ends of which are united by a curved portion 7 which engages on top of the upper 80 and 1² of the reinforcing bars. Formed integral with the lower ends of the legs 6 are extensions or foot portions 8, the lower corners of which rest directly upon the false work or form, and the corners between the upper edges of these extensions and the corresponding edges of the legs 6 are curved to 85 form seats 9 for the lower one B of the reinforcing bars. In this construction the weight of the supporting bars is utilized for causing the combined support and tie to clamp the reinforcing rods, the same as in the forms of the devices illustrated in Figs. 1 to 5 inclusive and heretofore described.

In Fig. 7 the device 10 similar in structure to the device shown in Fig. 6 is utilized for supporting a single rod and where such construction is employed a transverse supporting member 11 such as a wire nail takes the place of the lower rod B and forms the fulcrum for the supporting member.

In the form of the device illustrated in Fig. 8 the extensions 8 are provided with upwardly projecting bars 8¹ which are adapted to be bent downward over the upper pair A when the device is applied for use.

The form of device illustrated in Fig. 9 is adapted for supporting and tying together a pair of crossed rods and in this form the legs 3² occupy practically vertical positions instead of being inclined as is the case in the device shown in Figs. 6, 7, and 8.

The form of the device illustrated in Fig. 10 is practically the same as the device shown in Fig. 1 with the exception that it is formed of sheet metal instead of wire. The particular feature consisting of a pair of curved parallel legs 11 which straddle the upper reinforcing rod, a pair of short vertically disposed legs 12, and a pair of longer vertically disposed legs 13 to the lower ends of 14 which rest upon the false work or form upon which the floor or ceiling is laid.

The form of the device illustrated in Fig. 11 is substantially the same as the device shown in Fig. 10 with the exception that it is formed from a flat metal strap bent to proper shape. In this form of device the upper portions of the inclined legs 12 and 13 are bent, repeating the same procedure as to agency plates substantially at 140

right angles to the planes occupied by the vertical legs of the device.

In Fig. 12 I have illustrated a combined support and tie of the form seen in Fig. 1 and which support and tie is applied to a pair of reinforcing rods which occupy a vertical plane as is the case in the reinforcement of walls and the like. Where such construction is carried out the ends of the longer legs 15 of the device bear against the face of the false wall or form and the vertically disposed rod C is forced against the horizontally disposed rod D by a wedge or key 16 inserted between the outer portions of the pairs of legs of the device. This arrangement effectually ties the two rods together and holds the same a proper distance away from the surface of the false wall or form so that said rods are embedded in the concrete in the desired planes. In this form of the device the tying together of the rods is effected by means of the wedge or key instead of by the weight of the rods as is the case where the rods are horizontally disposed.

A device of my improved construction is comparatively simple, can be cheaply manufactured, is readily applied to reinforcing rods and automatically grips and ties the same together by reason of the weight of said rods.

The device when properly applied performs the functions of a lever, and the gripping action on the rods is obtained by the weight of said rods reacting through the support, which latter fulcrums upon the lower one of the supported rods, thus transmitting the resulting reaction through leverage to the upper rod, consequently tying the two rods together and supporting the same the desired distance above the surface of the false work or form.

It will be readily understood that minor changes in the size, form and construction of my improved support and tie can be made and substituted for those herein shown and described, without departing from the spirit of my invention, the scope of which is set forth in the appended claims.

I claim:

1. In a device of the class described, a pair of vertically disposed parallel legs provided with seats adapted to receive a reinforcing rod, a second pair of parallel legs projecting upwardly and outwardly from the first mentioned legs, the upper ends of which upwardly and outwardly projecting legs are united to form a seat for a second reinforcing rod which is positioned on top of and at right angles to the first mentioned reinforcing rod, and which seat is adapted

to engage the second mentioned reinforcing rod at a point a substantial distance to one side of the vertical plane occupied by the first mentioned reinforcing rod, whereby the weight of both rods reacting through the pairs of legs causes the device to grip both reinforcing rods.

2. A device of the class described comprising a pair of vertically disposed parallel legs, a second pair of parallel legs formed integral with and projecting upwardly and outwardly from the first mentioned legs, the upper ends of said upwardly and outwardly projecting legs being united to form a reinforcing rod engaging seat which is located a substantial distance to one side of the vertical plane occupied by the first mentioned pair of legs, and the lower portions of the upwardly and outwardly projecting legs being curved near the points where they unite with the vertically disposed legs to form a pair of horizontally aligned seats which are adapted to receive a reinforcing rod.

3. A device of the class described comprising a pair of parallel inclined legs, the upper ends of which are united to form a seat for a reinforcing rod, the lower portions of said legs being curved upward to form a pair of horizontally aligned seats adapted to receive a fulcrum member, and a pair of vertically disposed parallel legs integral with and extending downwardly from the lower portions of said inclined legs, the seat at the upper ends of the inclined legs being located a substantial distance to one side of the fulcrum, whereby the weight of the supported rod reacts through the device and causes the same to grip said rod.

4. In a device of the class described a continuous strip of metal bent at its central portion to form a seat and two parallel members extending downwardly at an angle therefrom, said parallel members being extended upwardly at their lower portions to form a pair of horizontally aligned seats, and thence downwardly to form a pair of vertical legs, the first mentioned seat being located at a substantial distance to one side of the second mentioned seat whereby the weight of reinforcing rods located in said seats will effect a tilting action and cause the said seats to hold the rods in position.

In testimony wherof I hereunto affix my signature in the presence of two witnesses, this 27th day of May, 1913.

GEORGE R. SCHOENTHALER.
